UNITED STATES PATENT OFFICE.

WENZEL HAUPT, OF NEW YORK, N. Y.

HELICOPTER.

1,414,410.

Specification of Letters Patent.

Patented May 2, 1922.

Application filed March 23, 1920. Serial No. 368,204.

To all whom it may concern:

Be it known that I, WENZEL HAUPT, a citizen of the United States, and resident of New York, in the county of New York and State of New York, have invented certain new and useful Improvements in Helicopters, of which the following is a specification.

This invention generally relates to propellers and in particular to the kind used for lifting and known as helicopters.

The primary object of my invention is to provide a device for lifting aircraft from the ground in a substantially vertical direction.

Another object of my invention is to construct such device in a manner as to impart thereto not only a high grade of lifting power but also the capacity of carrying properties.

In order to explain the principle of its construction it is necessary to elucidate the successive steps taken in the developing of my device.

The principle of a propeller is well known. When developing a plane into a propeller, the operation of which is based upon the principle of a pair of revolving blades of equal pitch, it will be found that the effective area of the propeller lies at or near its longitudinal center line. The lifting or propelling power depends upon the pitch of the blades.

The blade areas at both sides of the longitudinal center portion are not effective to the same degree, as to their lifting or propelling capacity, as the central area, since they are not within the radius of the propeller.

In order to make effective all or nearly all parts of the propeller it is necessary to create a plurality of radial units, each with an effective center area as large as possible.

Therefore I divide the original propeller planes in a multitude of individual double bladed propellers, the center line of each blade being disposed radially from the propeller center common to all divided propellers.

The operation of each revolving propeller in conjunction with the atmosphere is similar to that of a screw thread. Upon the grade of incline or the pitch of the blade

and upon the speed with which a propeller rotates depends the speed of travel of the 55 propeller.

If the pitch is small at a given number of revolutions the propeller will move forward slower than if the pitch is greater.

A propeller of small pitch, will have the 60 tendency of carrying similar to a circular stationary plane or a revolving flat-bladed propeller.

In order to achieve the desired combined results of carrying and propelling, I provide the individual blade propellers with different pitches, starting out at the top propeller with the smallest pitch and gradually increasing it toward the bottom propeller.

Still better results may be obtained by 70 spreading the individual propellers and setting them at certain angles in relation to each other, with their center lines lying in a parabolic curve.

With the foregoing arrangement I achieve 75 two very important objects, first in creating a shearing curve which gradually engages the atmosphere, and second in supplying surplus air from one propeller to the other.

The first object aids in overcoming the 80 air resistance, the second greatly increases the lifting or propelling power of my device, as the air deflected from the propeller first engaging the air is thrown in the path of the next following propeller. The deflected 85 air, otherwise lost, is partially compressed and acts as an additional air cushion in conjunction with the lower air-layer engaged by the second propeller.

With the varying pitches of the individual 90 propellers their widths vary accordingly, and with their width the effective propelling area changes in proportion.

In direct relation with the effective lifting or propelling area is the carrying power 95 of the propellers.

The smaller the effective propelling area is, the larger becomes the carrying capacity of the blades. Thus the blades of smallest pitch and consequently of smallest width 100 have the smallest propelling area but the largest carrying capacity. The greater the pitch of the propeller blades the wider they become, and the greater is their propelling area while the carrying capacity diminishes 105 in proportion.

The best results may be obtained when the propellers are evenly distributed within a sector of 90° , thus leaving a free space of 90° between the front of the top propeller 5 and the rear of the bottom propeller.

Another important feature of my device is the gradually increasing pitches of the blades varying in degrees by arithmetical progression, for instance starting with 10 9 degrees and terminating at 45 degrees. The arrangement of the propellers is of course not limited to any particular number and similarly the pitch variation may start at 15 any desired degree. It may seem that a similar result might be obtained by connecting the propellers to two symmetrical, parabolically curved planes or by overlapping the propellers. Such contention is erroneous, and experiments have proved that it is 20 absolutely necessary to provide individual and distinctly separated propellers in order to achieve the best of operating conditions in my device.

The foregoing explanation involving some 25 of the objects of my invention will be more clearly understood from the accompanying drawings, forming part of this specification, in which:

Figure 1 is a pair of diagrammatical views 30 of a plane.

Figure 2 is a pair of diagrammatical views illustrating the process of forming a propeller.

Figure 3 is a diagrammatical view of 35 one propeller blade divided in five equal parts.

Figure 4 represents the parts separated, the blade center lines indicating effective lifting areas at different pitches.

Figure 5 is a diagrammatical view illustrating the arrangement of blades in my 40 helicopter.

Figure 6 is a diagrammatical view of 45 blades illustrating the way air is deflected from one propeller into the path of the next following.

Figure 7 is a top view of a preferred form of my device.

Figure 8 is a top view of a single propeller. 50

Figure 9 is a sectional view therethrough taken on line 9—9 of Figure 8.

Figure 10 is a sectional view taken on line 10—10 of Figure 8.

Figure 11 is a side elevation of a single propeller. 55

Figures 12, 13, 14, 15 and 16 are diagrammatical views showing various pitches of five propeller blades.

Figure 17 is a side elevation of my device. 60

Figure 18 is a bottom view thereof.

Figure 19 is a typical enlarged section through a propeller blade.

Referring to the drawings, the successive 65 steps developing my helicopter may be

readily followed. The plane 10 (Fig. 1) is divided at its transversal center line 11 (Fig. 2), into two symmetrical wings 12 and 13, inclined at a certain angle or pitch, while the longitudinal center line 14 remains unchanged. Thus a double-bladed propeller is created. 70

It is obvious that in a comparatively wide propeller only a small strip in near proximity to the longitudinal center line of each 75 blade is radial, while the blade's edges are off center. The effective area of a propeller blade is at its longitudinal center line, and the ineffectiveness of a propeller blade due to this cause increases with its width. 80

Consequently I endeavor to create a larger number of effective areas while decreasing the less effective areas of a propeller.

This I accomplish by dividing the original large propeller in the way indicated in Figure 3, representing the propeller blade 12, and finally separate it into independent units seen in Figure 4.

By altering the pitch of each unit, placing the units on top of each other starting with 90 the unit of largest pitch at the bottom, and distributing the units radially at equal angles within a given sector, the blades will form a parabolic curve (Fig. 5).

Since the lifting and carrying powers 95 depend upon the pitch of the blades it is obvious that the blades of greater pitch will have more lifting capacity and less carrying power, while the blades of smaller pitch will act as carriers due to their reduced propelling power. 100

Thus the blades 15 and 16 (Fig. 5) will carry and blades 17, 18 and 19 will lift.

The lifting capacity of the thus constructed helicopter is greatly increased by 105 deflection of air from one propeller to, or in the path of the next following propeller when the device is in motion. See Figure 6.

The rotating blade 15 strikes the air indicated by arrow 20. The air is deflected at 110 the same angle at which it is struck by the blade as indicated by arrow 21. At the same time the propeller blade 16 strikes the air indicated at 22. The deflected air 21 is compressed to a certain degree, due to the motion of and depending upon the force with which the blade 15 strikes the air layer 20. The deflected and compressed air 21 reaches the air layers 22 and forms an air cushion against which the next following propeller 120 blade 16 strikes and upon which it, so to speak, glides upward.

The same process is repeated in the following propeller blades.

It will be observed that the blades receive 125 a convex-concave shape, which increases their efficiency still more.

In Figure 7 may be seen the radial arrangement of five propellers evenly distributed within a sector of 90° . Thus the angu- 130

lar distance from the longitudinal center line of one propeller to the other is $22\frac{1}{2}$ degrees.

The propellers are arranged above each other and have a common axis. Tangentially from the hub-like center 23 and parallel to the longitudinal center line, run the back edges 24 of the blades (see Figures 8, 9, 10 and 11), while their front edges 25 are broken at 26 and continue at 27 radially toward the hub center. The portions between the hub and the parallel blade portions thus form wedge-shaped connections of acute angles.

15 In consequence of the variation of pitch the thickness and width of the propellers changes according to the degree of the pitch angle. This may be observed in Figures 12, 13, 14, 15 and 16. The thin line squares 28 represent the original shapes from which the propellers are made, the dotted lines 29, 30, 31, 32 and 33 correspond to the various pitch angles of 9, 18, 27, 36 and 45 degrees respectively, and the curves represent the 25 inner surfaces of the blades.

While specific angles are mentioned it is obvious that they may be changed to suit different conditions.

Also the number of propellers may be 30 changed. For certain purposes three and even two propellers might suffice, while on the other hand a much larger number than five will be necessary to suit other conditions.

35 The propellers as shown in Figures 7, 17 and 18, are grouped in the aforementioned relation one on top of the other and their proportion of length and width is twenty to one. Experiments have demonstrated 40 this relation of dimensions to be preferable to any other. I reserve for myself the right however to make alterations to meet various requirements.

Obviously also the shape of the blades 45 may be changed from that shown, especially as to its straight ends, which may be rounded or receive other forms, also the curvature of blade proper may vary.

Generally I reserve for myself the right 50 to change, and, differently construct and improve upon my invention, for which I claim:

1. In a propeller, the combination of five parabolically arranged blade units placed on top of and connected with each other and 55 having a common central axis, each unit comprising a pair of symmetrical blades of equal pitch, said units being disposed at an angular distance of $22\frac{1}{2}$ degrees from each other, thus providing two free angular distances of 90 degrees between the top and bottom units, the pitch of these blade units varying by arithmetical progression from the first term of 9 degrees to the last term of 45 degrees, said blades being so disposed 60 that the upper or cutting edge of one blade

lies in the same plane with the lower or delivery edge of the adjacent blade.

2. In a propeller, the combination of a plurality of parabolically arranged blade units placed on top of each other and having a common central axis, each unit comprising a pair of symmetrical blades of equal pitch, said units being disposed in relation to each other at equal angular distances within an angle of 90 degrees, thus 70 providing two free angular distances of 90 degrees between the top and bottom units, the pitch of these blade units differing by arithmetical progression from a given angular first term to a given angular last term, 80 said blades being so disposed that the upper or cutting edge of one blade lies in the same plane with the lower or delivery edge of the adjacent blade.

3. In a propeller, the combination of a plurality of parabolically arranged symmetrical blade units of differing pitch placed on top of and connected with each other and having a common central axis, said units being disposed in relation to each other at 90 equal angular distances leaving free spaces between each group of blades, the pitch of the units gradually increasing from top to bottom, said blades being so disposed that the upper or cutting edge of one blade lies 95 in the same plane with the lower or delivery edge of the adjacent blade.

4. In a propeller, the combination of a plurality of parabolically arranged symmetrical blades of gradually decreasing pitch 100 grouped and connected with each other at equal angles and having a common central axis, said blades being so disposed that the upper or cutting edge of one blade lies in the same plane with the lower or delivery 105 edge of the adjacent blade.

5. A helicopter comprising a plurality of individual propeller blades mounted one above the other, grouped in a parabolic curve and varying in their respective pitches, said 110 propeller blades having a common central axis and being disposed at equal angles to each other, said blades being so disposed that the upper or cutting edge of one blade lies in the same plane with the lower or delivery 115 edge of the adjacent blade.

6. A helicopter comprising a plurality of individual propellers arranged radially above each other at equal angles and forming two symmetrical groups of parabolically arranged propeller blades, each group within a sector of 90 degrees, thus providing a pair of free opposite disposed sectors of 90 degrees between the blade sectors, said propellers being of various pitches, the uppermost propeller having the smallest pitch, the lower-most propeller being of largest pitch, the propellers being grouped so that their center lines lie in a parabolical arc, 120 said blades being so disposed that the upper 125 most propeller having the smallest pitch, the lower-most propeller being of largest pitch, the propellers being grouped so that their center lines lie in a parabolical arc, said blades being so disposed that the upper 130

or cutting edge of one blade lies in the same plane with the lower or delivery edge of the adjacent blade.

7. A helicopter comprising a plurality of 5 individual radially disposed bladed propellers, the blades arranged above and at equal angles to each other, and comprising blade groups, said blade groups forming blade group sectors, so disposed as to leave between 10 them free sectors, the propeller blades having various pitches, and arranged to form two symmetrical parabolic arcs, said blades in said blade groups being so disposed that the upper or cutting edge of one blade lies 15 in the same plane with the lower or delivery edge of the adjacent blade.

8. In a helicopter comprising a plurality of individual propellers of various pitch arranged above each other in parabolic curves 20 and radially extending from their common center at equal angles within a given sector, a propeller blade having a center portion forming a hub, a pair of symmetrical convex-concave wings the center-line of which 25 coincides with the longitudinal center-plane of the hub, acutely tapered connections uniting said wings with the hub, and having their front edges disposed radially from the center axis of the hub, the blades of said 30 propellers being so disposed that the upper or cutting edge of one blade lies in the same plane with the lower or delivery edge of the adjacent blade.

9. A helicopter comprising a plurality of 35 parabolically grouped propellers of various pitch, arranged radially and above each other, the upper propeller of lesser pitch adapted to serve as carriers, the lower propellers of greater pitch serving as lifters, 40 said propellers being so disposed that their upper and lower edges of two adjacent propellers lie in the same plane.

10. A helicopter comprising in combination a plurality of lifting and carrying propellers arranged in parabolic curves, the 45 former having a greater pitch than the latter, so that the upper edge of one propeller lies

in the same plane with the lower edge of the adjacent propeller.

11. A helicopter comprising a combination of a plurality of parabolically grouped lifting and carrying propellers, the former being of greater pitch than the latter, the delivery edge of each propeller of lesser pitch lying in the same plane with the cutting edge of the next following propeller of greater pitch, whereby air is deflected from one propeller in the path of the other. 55

12. A helicopter comprising a combination of a plurality of parabolically grouped lifting and carrying propellers, said propellers being so disposed that the upper edge of one propeller lies in the same plane with the lower edge of the adjacent propeller, each propeller adapted to individually engage the 60 atmosphere and transmit the engaged atmosphere toward and in the path of the next following propeller.

13. A helicopter comprising a plurality of 70 parabolically grouped individual radially disposed propellers of different pitches, said propellers being so disposed that the upper edge of one propeller lies in the same plane with the lower edge of the adjacent propeller, each propeller adapted to individually engage the atmosphere when the helicopter is revolved.

14. A helicopter comprising a plurality of 75 parabolically grouped radially disposed propellers the length and width of which are proportioned twenty to one, the upper and lower edges of two adjacent propellers lying in one plane.

15. A helicopter comprising a plurality of 80 parabolically grouped propellers having 85 convex-concave propeller blades arranged in a parabolic curve and adapted to transmit air from one blade to the other, the upper and lower edges of two adjacent propellers lying in one plane. 90

Signed at New York city, in the county of New York, and State of New York, this 22d day of March, A. D. 1920.

WENZEL HAUPT.
